Primary Examiner — Kimberly Barnes(74) *Attorney, Agent, or Firm* — Gardner Groff & Greenwald, PC(57) **CLAIM**

The ornamental design for a vacuum cleaner, substantially as shown and described.

DESCRIPTION

FIG. 1 is a perspective view of a vacuum cleaner according to the design.

FIG. 2 is a front view of the vacuum cleaner of FIG. 1.

FIG. 3 is a back view of the vacuum cleaner of FIG. 1.

FIG. 4 is a first side view of the vacuum cleaner of FIG. 1.

FIG. 5 is a second (opposite) side view of the vacuum cleaner of FIG. 1.

FIG. 6 is an enlarged top view of the vacuum cleaner of FIG. 1; and,

FIG. 7 is an enlarged bottom view of the vacuum cleaner of FIG. 1.

The broken lines in the figures depict portions of the vacuum cleaner that form no part of the claimed design.

1 Claim, 7 Drawing Sheets
